UNITED STATES PATENT OFFICE.

ARCHIBALD B. HEATH, OF LYNBROOK, NEW YORK.

DESIGN FOR A LAMP.

Application filed July 1, 1924. Serial No. 10,024. Term of patent 14 years.

To all whom it may concern:

Be it known that I, ARCHIBALD B. HEATH, sign.
a citizen of the United States, residing at Lynbrook, in the county of Nassau and State of New York, have invented a new, original, and ornamental Design for Lamps, reference being had to the accompanying drawing, forming part thereof.

Figure 1, is a front view of the new design. Figure 2, is a side view thereof, and Figure 3, is a top plan view.

I claim:

The ornamental design for a lamp, as of which the following is a specification, shown.

ARCHIBALD B. HEATH.
